S. B. Gardner

United States Patent Office.

S. B. GARDNER, OF FREEPORT, ILLINOIS, ASSIGNOR TO HIMSELF AND ABRAHAM H. LEEDY.

Letters Patent No. 95,677, dated October 12, 1869.

IMPROVED RAILWAY-CAR-BRAKE SHOE.

The Schedule referred to in these Letters Patent and making part of the same.

To all whom it may concern:

Be it known that I, S. B. GARDNER, of Freeport, in the county of Stephenson, and State of Illinois, have invented an Improved Shoe for Car-Brakes; and I do hereby declare that the following is a full and exact description thereof, which will enable those skilled in the art to make and use the same, reference being had to the accompanying drawing, and letters marked thereon, making a part of this specification, in which—

Figure 1 is a perspective representation of my improved shoe.

Figure 2, a vertical central section of the same.

The nature of the present invention consists,

First, in providing the brake-block with a metal lining, to prevent it from taking fire from the friction-plate, when heated.

Second, providing the bolt-holes through the brake-block with metal thimbles or linings, to prevent the bolts, which hold the friction-plate to the block, from communicating fire to the latter, as the whole is hereinafter fully described.

A represents the ordinary brake-block, and B, the beam to which it is attached in the usual manner.

C represents the friction-plate, which has a peculiar construction, as follows:

The usual lugs F H are cast to the inner side, to separate it from the block A, but grooves G G, figs. 1 and 2, are made in it, and recesses I I are made in the margin of the grooves, to receive the heads E E, of the bolts J, which hold it on, in order that the

plate C may be held in place, without subjecting the heads of the bolts J to the wear of the car-wheels.

This method of fastening the plate C, however, is not novel, the detailed description thereof being given, that all parts of the shoe, as it is made, may be readily understood.

The device for preventing the block A from taking fire by the heat caused by the friction of the car-wheel on the plate C, consists,

First, of a metal plate, D P, placed between the friction-plate C and the block A.

Second, in the application of thimbles L L to the holes through which the bolts J, in the block A, pass, for holding the friction-plate C in place.

These thimbles are provided with flanges x, fig. 2, projecting outward and under the plate D P, far enough to be held in place, when all parts of the device are put together, as shown at fig. 1

Having thus described my invention,

What I claim, and desire to secure by Letters Patent of the United States, is—

1. In combination with the friction-plate C and block A, the plate D P, for preventing the block from taking fire, as set forth.

2. In combination with the friction-plate C and plate D P, the thimbles L, put around the bolts J J, as and for the purpose set forth.
